CLAIM

The ornamental design for a ventilation port as shown and described.

DESCRIPTION

FIG. 1 is a rear perspective view of a ventilation port showing the new design.

FIG. 2 is a front perspective view of the ventilation port showing the new design.

FIG. 3 is a rear elevational view thereof.

FIG. 4 is a front elevational thereof.

FIG. 5 is a left side elevational thereof.

FIG. 6 is a right side elevational view thereof.

FIG. 7 is a top plan view thereof; and,

FIG. 8 is a bottom plan view thereof.

The broken lines in the drawings depict portions of the ventilation port that form no part of the claimed design.
